UNITED STATES PATENT OFFICE

2,357,369

TURRET SHAPING MACHINE FOR CIGARS

Henry H. Wheeler, Brooklyn, N. Y., assignor to
International Cigar Machinery Company, a cor-
poration of New Jersey

Original application July 16, 1938, Serial No.
219,509. Divided and this application August
21, 1940, Serial No. 353,469

19 Claims. (Cl. 131—87)

This invention relates to cigar machines and more particularly to machines for forming cigars of the short filler type wherein there is provided a series of traveling pockets or molds in which bunches are shaped prior to being rolled and formed into complete cigars.

This application constitutes a division of my co-pending application Serial Number 219,509, filed in the United States Patent Office on July 16, 1938.

The chief object of the invention is to improve the operation of the machine described in my Patent No. 2,157,537. In the machine of the patent above referred to, raw cigar bunches are transferred manually from a bunch rolling apron by an operator at the loading station into open molds formed in the pockets of the intermittently revolving drum or turret provided for this purpose and shaping members or covers are then fitted into these molds and remain therein during at least one-half revolution of the turret. In one position along the path of travel of the turret, transfer arms lift a shaping cover from one of the closed molds containing a fully shaped cigar bunch and transfer it to a diametrically opposite mold wherein is located an unshaped cigar bunch.

According to the present invention, mechanism has been provided for more efficiently removing the covers from the molds and transferring them to cover applying position, hence it is an object of the invention to provide improved cover handling and transfer mechanism.

It is a further object of the invention to provide a cover transfer mechanism in which covers are aligned and centered prior to their application to open molds in order to eliminate breakage of the transfer arms.

It is a further object to provide gripper mechanism on the arms which travel with the turret for a portion of its rotation during each cycle of the machine in order that the transfer of covers from one mold to another may be more accurate and positive.

The invention is further characterized by the provision of an improved latching device for effecting the movement of the cover transfer arms to and from mold cover removing and replacing positions.

From time to time it has been found that gum and tobacco particles tend to build up deposits on the cover transfer mechanism and for that reason cleaning means have been provided along the path of movement of the transfer arms in order that the portion of the grippers which gen-

erally receive these deposits may be kept clean by means of brushes or like mechanism.

It is a further object of the invention to provide a movable guard plate associated with the cover transfer arms which operates normally to prevent access of waste material to machine parts and which is rendered inoperative by movement of the transfer arms during each removal operation of a cover from a mold.

10 It is a further object of the invention to provide means for more perfectly locating the cover transfer arms by the provision of adjustable abutments at the cover applying position which makes it possible to adjust the abutments and 15 maintain them in adjusted position at all times.

With these and other objects not specifically mentioned in view, the invention consists in certain combinations and constructions which will be hereinafter fully described, and then specifically set forth in the claims hereunto appended.

In the accompanying drawings which form a part of this specification, and in which like characters of reference indicate the same or like parts:

25 Fig. 1 is an end elevation partly in section, of the improved shaper turret and the scrap disposal means associated therewith;

Fig. 1a is a partial side elevation of the improved locking means;

30 Fig. 1b is a sectional end elevation of the locking means shown in Fig. 1a;

Fig. 2 is a sectional side elevation of the shaper turret, on line 2—2 of Fig. 1, including views from lines 2' of Fig. 1;

35 Fig. 2a is a cross-sectional view taken on line 2a of Fig. 5 showing a detail in the construction of the cover gripping mechanism;

Fig. 3 is a partial plan view from line 3—3 of Fig. 1 showing a detail of my invention;

40 Fig. 4 is a partial side sectional elevation of Fig. 3; and

Fig. 5 is a fragmentary sectional view on an enlarged scale showing details of the cover holding and transferring mechanism.

45 The drum 29, which carries the bunch shaping molds 30 in pockets 23 (Figs. 1 and 2) is intermittently rotated by mechanism, similar to that shown in my Patent No. 2,157,537 above referred to, in the direction of arrow 10 in steps 50 equal to the angular distance between each pocket. The bunches formed on the bunch rolling machine are inserted by an operator into any one of the molds which are open at position I, which corresponds generally from the 12:30 to 55 the 2:30 o'clock position of the turret drum.

By providing a plurality of open pockets at the loading position, it is possible to more easily fill the molds, and sufficient time can be allowed so that danger of injury to the operator is reduced to a minimum. The turret is indexed to position II, which approximates the 3 o'clock position, where a positioning member 66 actuated through slide 64 by rollers running in tracks 69 and 70 formed on the interior face of the cams 60 and 63 fixed on drum shaft 50, is moved partly into the mold to seat the bunch located therein and is immediately withdrawn. Slide 64 is actuated in a manner similar to that shown in my Patent No. 2,157,537 issued May 9, 1939, for Cigar bunch shaping machine. At station IV, or the 4 o'clock position of the turret, which the next point in the indexing thereof, a shaping and compressing member 67, similar in construction and operation to member 66, is moved completely into the mold on slides 65 to fully shape a bunch therein, and then withdrawn before the turret is indexed to move the next mold into position for cooperation with the shaping member 67. Slides 64 and 65 travel in slots (see Fig. 1) formed in plates 54 and 55.

Station V, where the mold covers 31 are put into place by means of transfer arms 77, in the preferred embodiment, is located prior to the 6 o'clock position. The transfer arms 77, which consist of bifurcated central portions or cross heads 780 supported on shaft 50 by blocks 79 rotatable on shaft 50, are actuated by rollers 80 secured to said arms 77 by means of suitable pins 190 which engage and run in tracks 81 formed on the peripheries of cams 60 and 63. After covers 31 have been applied to their respective mold pockets, they remain thereon during the travel of the turret through approximately 180°, or one-half revolution, as shown in Fig. 1. The upper ends of arms 77 lift a cover 31 from one mold 30 while at the same time the lower ends are inserting the previously lifted cover into the diametrically opposite mold. The arms 77 are latched to cams 60, 63 by means described more fully hereinafter, while the latter make one-half a revolution in a counterclockwise direction, indicated by arrow 11 in Fig. 1, and at the same time because the arms 77 are latched thereto, they necessarily must travel through 180° in the same direction as indicated by arrow 12. Shaft 50 and cams 60 and 63 mounted thereon are rotated continuously in a counterclockwise direction. At the conclusion of each 180° movement, the arms are again moved radially upward in order to operate successive covers of the molds in a similar manner.

As shown in Fig. 2, an ejector plate 56 is slideable within the drum 29, and carries ejector pins 57 which are arranged with ejecting surfaces of bunch shaped contour to lift bunches shaped in pockets 23 of the drum. A cam roller 59 on the plate 56 engages the innermost tracks of cam 60 which serve to control the ejecting movement of the pins 57. All of this structure is similar to that shown and described in my Patent No. 2,157,537.

To align the covers 31 properly while they are carried by the arms 77, the latter are equipped with gauging devices to hold all covers in the same axial position with respect to the mold pockets 23, and with centering devices to keep them axially parallel in that position. The gauging device consists of adjusting screws 14 inserted horizontally into the ends of arms 77 and

coaxial with the centers of non-rotatably mounted wear-resisting collars 34 on the end projections 33 of the covers. These screws, after adjustment to the exact overall length of the covers, 5 are held firmly in position by set screws 15. The centering device consists of bell crank levers 16 pivoted on horizontal pins 17 in the ends of arms 17 and held in tension by springs 18 inserted into axial cavities in arms 17, these springs pressing against the radial arms 162a of levers 16. The axial arms 162 of the levers 16 are made with axially extending depressions 160 into which the collars 34 snap when they have entered the mold cover collar supporting pockets formed by the ends 340 of the arms 17 and the arms 162 of levers 16 with depressions 160, thereby holding covers 31 securely in exact angular position in the arms 17 and relative to the mold pockets while being transferred.

Improved mechanism has been provided for more securely latching the transfer arms 77 to the cams 60 and 63 while being rotated by them. This structure consists of lock levers 19 pivotally mounted on pins 20 fixed to the outer surface 25 of the cams, which levers are formed with depressions 810 for locking the rollers 80 when the latter are in their dwell position on the low points of the cam tracks 81 as shown in Fig. 1. It will be observed that a locking action, which for want of a better expression is termed a "toggle" action, is set up by the depressions 810 of the locking levers 19 and cam tracks 81 as shown at Fig. 1 so that during the counterclockwise movement of the arms 77 while latched to lever 19 35 there can be no possible interruption of the locking operation until roller 25 mounted on lever 19 engages pin 26 and lifts lever 19 out of engagement with rollers 80. The lines AB and BC (Fig. 1a) indicate the two forces which would 40 act to hold the rollers firmly between the cam tracks 81 and the depression 810 whenever an obstruction tends to retard the rotary movement of arms 77 and rollers 80 mounted thereon. The arm 19 may be considered to constitute one link 45 of a toggle and the pin 190 of roller 810 may be regarded as the fulcrum of the roller 810. The counterclockwise movement of arms 77 from position V through 180 degrees of travel, therefore, causes roller 80 to be forced along a line through the center of depression 810 and pivot 20 so that in effect roller 80 is wedged in depression 810 until released as above stated. The form of the cam tracks 81, as shown in Fig. 1, is such that after the empty end of the arms 77 is stopped at the 50 cover-removing station of the turret, the rotation of the cam tracks 81 relative to the rollers 80, displaces the transfer arms 77 upwardly, so that the ends 340 of said arms and the arms 162 of levers 16 are in position to admit the collars 34 55 of one of the covers 31 therebetween during the next advance of the turret. As in my Patent No. 2,157,537 above referred to, as a result of the continued motion of cams 60 and 63, the high part of the cam surface 81 lifts the transfer arms 77 to the position shown in Fig. 1, in which the arms become latched to the cams by the lock levers 19 described above. Since the transfer arms 77 prior to the indexing of the turret have 60 been positioned with their empty cover transferring ends in the path of collars 34, at the conclusion of each turret movement the collars 34 on a cover to be removed will have been located in the grippers on the upper ends of the arms so that the cover is moved outwardly and away from 65 70 75

its mold pocket with the outward movement of the transfer arms (see Figs. 1 and 2). Due to the fact that the transfer arms are firmly latched to the cams 60 and 63, during the continued rotation of the cams, the transfer arms 71 will travel in unison therewith through 180°, or until the outer ends of the transfer arms strike against the abutments 86 mounted on the bracket 53 and rollers 25 engage pins 26 to unlatch rollers 80 from engagement with the low point on the cam tracks 81. Continued movement of the cams 60 and 63 causes the rollers 80 to be moved radially, thereby raising the cover supported on the lower ends of the transfer arms into alignment with the tracks 87 at which position the transfer arms dwell while the drum 29 is indexed forwardly. The cover 31 which has just been moved into a mold by the transfer arms, is thus removed circumferentially from the ends of the arms by the movement of the turret and is thereafter controlled by the tracks 87. In the continued motion of the cams 60 and 63 the high part of the cam surface 81 lifts the arms 71, thereby carrying the end of the transfer arms which have just discharged a mold covered to the position shown in Fig. 1, at which time the pockets at the upper end of the transfer arms lift a cover, as shown at the top portion of Fig. 1, ready to repeat the cover transfer operation. When the transfer arms are positioned as shown in Fig. 1, the lock levers 19 engage with the rollers 80, then at the lower dwell points of track 81, and latch the transfer arms to their cams so that on further movement of the cam, the transfer arms will be again moved 180° from cover receiving to cover applying position. When the cams have completed their next half turn and when the ends of arms 71, which are shown in their up position in Figs. 1 and 2, have come into engagement with abutments 86, the rollers 25 of lock levers 19 engage pins 26 inserted into the stationary frames 54 and 55, thereby releasing the transfer arm rollers 80 and allowing the cams 60, 63 to turn through the next 180° without the transfer arms. During this free movement of the cams, the rollers 25 of the lock levers 19 may rest on or adjacent the rims 19a of the cams, leaving an adequate space between the lock levers 19 and the tracks 81 for the entrance of the rollers 80 at the end of the free half-turn of the cams. The lever 19 is not solely dependent on spring 21 for its locking action. Pin 20 is so positioned that a "toggle" action is obtained between lever 19 and roller 80 which is locked in depression 810 of lever 19, the roller 80 being forced more firmly against cam track 81, in direct proportion to the increase in resistance of arm 71. Pin 26 is therefore, provided to furnish positive means for lifting lever 19 out of engagement.

In order to secure perfect alignment of the two transfer arms while carrying the mold covers 31 from the top to the bottom of drum 29, the abutments 86 at each side of the drum are made in the form of separate plates, radially adjustable by means of set screws 83 carried by a projection 84 of bracket 53 and by a lug 85 on gear housing 62, respectively. In setting up the machine, these plates are so adjusted that neither arm 71 is free to turn before the other has cleared its plate, hence both arms commence their movement from identical angular positions at exactly the same instant.

To prevent dust or tobacco fragments from entering into the working parts of the turret at

the runways of arms 71, covers 35 tensioned by springs 36 are hinged to the tops of frames 54 and 55, these covers being opened by the arms 71 when the latter are raised in their dwell position, and automatically closed as the arms move away therefrom to transport a cover for application to a mold. The closing action is effected by means of springs 36 which continuously urge the covers 35 into closed position. In their closed position, as shown in dotted lines in Fig. 1, projections 37 of the covers 35 fit into cut-outs 370 (Figs. 3 and 4) in frames 54 and 55, and serve as stops for the arms 71 against any possible angular retrograde movement when arriving in their dwell position prior to their radial outward motion. The stops 37, being part of the cover 35, are pressed into position by means of spring 36, as soon as the arms 71 move away from their dwell position to complete a 180° rotation, as mentioned above. A further precaution against the entrance of foreign matter is provided by a set of brushes 32 attached to the lower surfaces of the frames 54 and 55, these brushes being in the paths of the inner surfaces 161 of the pocket portions of arms 71 (see Figs. 2 and 2a) and thus prevent accumulation of tobacco fragments on these surfaces.

The improved mechanism for cutting the overhanging ends of the cigar bunches constitutes the subject matter of my prior application, Serial Number 219,509, of which the present application constitutes a division. The improved trimming mechanism described in said parent application is placed at trimming station III. In brackets 38 on frames 54 and 55 is supported a shaft 40 on which are fastened at the proper distance adjustable to the length of the bunches operated upon, blocks 41 carrying lenticular shaped knife blades 42. It will be noted that blocks 41, upon which knives 42 are mounted, are shaped more or less like paddles, and due to their proximity to the chute 71 function after the severing of an end from a bunch of the pocket to eject or flip the cut off portions of tobacco down the chute and in that way constitute an efficient means for positively disposing of the cut off bunch ends.

The scraps from the trimmed bunches fall into a chute 71, removably supported between the brackets 38, Fig. 1. This chute may be secured near the inner end of each of its side walls by a suitable member 72, to the brackets 38 and near its outer end carries posts 73 which fit into holes 74 drilled for this purpose into the radial top surface of bracket 53. The movable cutters 42 are so located with respect to the waste discharging chute 71 that the knives assist in the removal by centrifugal force from the knives, of any tobacco tending to cling thereto which is not removed by the cutting action of the knives themselves. The blocks 41 serve to impart a push to the cut off portions to start the same sliding down the chute. It has been found that by giving the cut off portions a start down the chute, the portions will continue to travel down the chute 71 and jamming thereon will be thus avoided. In this manner the knives are also kept substantially clean at all times.

From chute 71, the scrap is delivered into a chute 75, (Fig. 1), supported in the base frame of the cigar machine and terminated in an elbow 76. This elbow enters into a box 78 and therein is closed by a valve 79 hinged on a pin 82 turnable by a crank arm 89 actuated through a connecting rod 90 from a crank lever 91 held

in engagement with its cam by a spring 92. A tubular extension of the stationary box 78 enters into a closed drawer 93 slidable in the base of the machine and also having entering into it an elbow 94 at the end of a pipe 95 connected with the suction system of the machine. At regular cyclic intervals, when the valve 79 is opened by the action of lever 91, the scrap accumulated in elbow 76 is drawn by the suction into drawer 93 which is emptied from time to time.

The invention above described may be varied in construction within the scope of the claims, for the particular device, selected to illustrate the invention, is but one of many possible concrete embodiments of the same. The invention is not, therefore, to be restricted to the precise details of the structure shown and described.

What is claimed is:

1. In a cigar machine provided with an intermittently moving series of bunch shaping pockets moving in an endless path, a plurality of covers adapted to be placed in said pockets for shaping bunches located therein, and mechanism for removing a cover from one pocket at one position along said path and applying it to an open pocket at another position on said path; a rotating member, a cover transfer arm adapted to travel with said member for a part of each revolution thereof, means for latching said arm to said member during said conjoint travel, said means comprising a latch lever carried by said member, a cam follower mounted on said arm and engaging said lever, and means for holding said lever and follower in close engagement.

2. In a cigar machine, the combination with a series of bunch shaping pockets, of mechanism moving said pockets in an endless path and presenting a plurality of said pockets open for loading, bunch shaping covers for said pockets, means for removing said pocket covers from said pockets radially of said path at one part of the path, and replacing said covers on pockets at another part of said path, said means comprising transfer arms located adjacent said pockets, grippers comprising spaced members formed in the ends of each of said arms and arranged to hold the ends of each of said covers, and means forming a part of one of said gripper members for centering said covers during said transfer from one point to another by said grippers.

3. In a cover transfer device for a cigar machine having a turret provided with a series of bunch shaping molds, and covers cooperating therewith for shaping bunches located therein, a rotatable arm, means forming a cover holding gripper on one end of said arm, including a stationary jaw, a resiliently mounted lever movable relative thereto, and means for urging said lever into gripping position to hold a cover clamped therein between said jaw and lever.

4. A cover transfer device for transferring covers in a cigar machine from one point to another, comprising an arm, a cover transfer gripper formed in one end of said arm, including an extension formed integral with and at right angles to said arm, a pivoted lever cooperating with said extension and forming a jaw of said gripper, and means for urging said lever towards said extension into gripping position to clamp a cover therein.

5. In a cigar machine, provided with a traveling turret having a series of bunch shaping pockets moving in a circular path, and a plurality of covers adapted to be placed in said pockets for

shaping bunches located therein; transfer arms positioned adjacent the ends of said turret, means comprising a pair of relatively movable opposed spaced gripper jaws on each of said arms arranged to admit portions of the cover therebetween for gripping said covers for removing them from said pockets at one position in the path of travel of said turret and replacing them at another position, means for yieldingly holding one

10 of the jaws on each of said arms in position to clamp the admitted cover portions against the opposed jaw, rotatable operating members, and mechanism for locking said arms to said members for travel therewith during a part of the revolution of said members.

6. In a cigar machine, the combination with a multimold bunch shaping turret for shaping cigar bunches, of a plurality of covers for said molds, mechanism for transferring successive molds to open molds diametrically opposite the point of removal, said mechanism comprising arms located adjacent the ends of said turret, grippers provided with relatively movable jaws mounted on the ends of said arms, the surface of 15 one of the gripper jaws being provided with a longitudinal groove for seating said cover therein, and means for moving said arms to effect the transfer of said covers.

7. In a cigar bunch shaping machine, the combination with a series of bunch shaping molds, of mechanism for moving said molds in a circular path, bunch shaping covers for said molds, mechanism for removing a cover from a mold at 20 one part of the path and replacing it on a pocket at another part of the path, said mechanism including transfer arms positioned to extend from one cover engaging part of the path to another part thereof diametrically opposite, gripper members fixedly formed on the opposite ends of each 25 arm, means coacting with each of said members to hold an end of said cover yieldingly against said gripper members during their transfer from one part of the path to the other, and means for imparting transverse and swinging motion to said arms to effect their transfer.

8. In a cigar machine provided with a series of cigar shaping molds moving in an endless path, a plurality of covers arranged to be placed in said molds for shaping bunches located therein,

30 and mechanism for removing a cover from one mold at one position along said path and applying it to an open mold at another position along said path; a rotating member, a cover transfer arm adapted to travel with said member for a part of each revolution thereof, grippers formed on the end of said arm, said grippers having resiliently mounted thereon means for yieldingly clamping said covers for transfer from one of said 35 positions to another, means for latching said arm to said member including a lever carried by said member, a cam follower mounted on said arm, and means for holding said lever and follower in close engagement.

9. In a cigar machine, the combination with a carrier intermittently rotating in a circular path, said carrier being provided with a plurality of molds, and a plurality of mold covers; mechanism for removing a cover from a mold at one part of the path, and replacing said cover on another mold at another part of said path, said mechanism including an arm extending from one position along said path to a diametrically opposite one, operating means for giving said arm movement transverse to said path to remove said

covers, and swinging movement to translate said covers along said path, and means separate from said operating means to prevent retrograde movement of said arm at the conclusion of said swinging movement.

10. In a cigar machine, the combination with a carrier provided with a plurality of bunch shaping molds, bunch shaping covers for said molds, a removal station where covers are removed from said molds, a station where covers are applied to molds, means for transferring covers from said removal station to said applying station, and a pivotally mounted guard plate located at said removal station for preventing access of foreign material to parts of said machine.

11. In a cigar machine, the combination with an intermittently rotating carrier moving in a circular path, and provided with a plurality of bunch shaping molds, bunch covers for said molds, a cover removing and a cover applying station located at spaced points along said path, transfer arms operative at said first-named station to remove a cover and transfer it with a transverse and a swinging movement from said removing station to a swinging movement from said removing station to said applying station, a pivoted guard plate for preventing the access of waste into parts of said machine, and means mounted on said plate for preventing the retrograde movement of said arms following their movement to said applying station.

12. In a cigar machine provided with an intermittently moving series of bunch shaping pockets moving in an endless path, a plurality of covers adapted to be placed in said pockets for shaping bunches located therein, and mechanism for removing a cover from one pocket at one position along said path and applying it to an open pocket at another position on said path, a rotating member, a cover transfer arm adapted to travel with said member for a part of each revolution thereof, means for latching said arm to said member during said conjoint travel, and separate means engaging with said latching means for releasing said latching means at the completion of said conjoint travel.

13. In a cigar machine provided with an intermittently moving series of bunch shaping pockets moving in an endless path, a plurality of covers adapted to be placed in said pockets for shaping bunches located therein, mechanism for removing a cover from one pocket at one position along said path and applying it to an open pocket at another position on said path, a rotating member, a cover transfer arm adapted to travel with said member for a part of each revolution thereof, means for latching said arm to said member during said conjoint travel, said means comprising a latch lever carried by said member, a cam follower mounted on said arm and engaging said lever, means for unlatching said arm at the end of said conjoint travel, and means for holding said lever and follower in close engagement.

14. In a cigar machine having a turret provided with a series of bunch shaping molds and covers cooperating therewith for shaping bunches located therein, a rotating cam, a rotating arm for gripping said covers to transfer them from one bunch shaping mold to another bunch shaping mold, a cam follower attached to said arm for actuating said arm, and means for locking and unlocking said cam follower to and from said rotating cam.

15. In a cigar machine having a turret pro-

vided with a series of bunch shaping mold pockets and covers cooperating therewith for shaping cigar bunches located in said pockets, a continuously revolving member, a transfer arm for engaging and transferring said covers from one bunch shaping mold to another bunch shaping mold, and means for locking said transfer arm to said continuously revolving member during certain predetermined periods of the machine cycle.

16. In a cigar machine having a turret provided with a series of bunch shaping mold pockets and covers cooperating therewith for shaping cigar bunches located in said pockets, a continuously revolving member, a transfer arm for engaging and transferring said covers from one bunch shaping mold to another bunch shaping mold, means for reciprocating said arm at a predetermined period of the machine cycle to replace one mold cover on a pocket and remove another mold cover from another mold pocket, and a locking device for locking said transfer arm to said revolving member for a predetermined period during each machine cycle to cause the covers held by said arm to be transferred.

17. A cigar machine having a turret, a plurality of bunch shaping mold pockets connected thereto, covers cooperating with said pockets for shaping cigar bunches located therein, a continuously revolving member, a transfer arm for engaging and transferring said covers from one bunch shaping mold to another bunch shaping mold, and a "toggle" device for locking said transfer arm to said continuously revolving member during predetermined periods of the machine cycle.

18. In a device for removing mold covers from the mold pockets at one station of a multimold bunch shaping turret, said mold covers having projecting ends carrying cylindrical parts, the combination with a plurality of members arranged to engage one side of the cylindrical parts on the projecting ends of the mold cover at said station of the turret, yielding grippers supported by said members and opposed to the portions of said members engaging said cylindrical parts and adapted to engage the side of said cylindrical parts which is opposite to the side engaged by said members and thereby clamp the cylindrical parts between said members and grippers, means supported by said members for preventing substantial longitudinal displacement of said covers while they are being removed, and means for operating said members to remove from its pocket the cover whose cylindrical parts are clamped between said members and grippers.

19. In a device for removing mold covers from the mold pockets at one station of a multimold bunch shaping turret, said mold covers having projecting ends carrying cylindrical parts, the combination with a plurality of members arranged to engage one side of the cylindrical parts on the projecting ends of the mold cover at said station of the turret, yielding grippers supported by said members and opposed to the portions of said members engaging said cylindrical parts and adapted to engage the side of said cylindrical parts which is opposite to the side engaged by said members and thereby clamp the cylindrical parts between said members and grippers, and means for operating said members to remove from its pocket the cover whose cylindrical parts are clamped between said members and grippers.

HENRY H. WHEELER.

CERTIFICATE OF CORRECTION.

Patent No. 2,357,369.

September 5, 1944.

HENRY H. WHEELER.

It is hereby certified that error appears in the printed specification of the above numbered patent requiring correction as follows: Page 4, second column, line 20, claim 6, before the word "molds" first occurrence, insert --covers from successive--; and that the said Letters Patent should be read with this correction therein that the same may conform to the record of the case in the Patent Office.

Signed and sealed this 14th day of November, A. D. 1944.

Leslie Frazer
